UNITED STATES PATENT OFFICE.

ARTHUR A. MOTT, OF SUMMIT, CALIFORNIA.

TIE-PLATE FOR USE ON RAILWAYS.

SPECIFICATION forming part of Letters Patent No. 791,202, dated May 30, 1905.

Application filed August 24, 1904. Serial No. 221,983.

To all whom it may concern:

Be it known that I, ARTHUR A. MOTT, a citizen of the United States, residing at Summit, in the county of San Bernardino and State of California, have invented new and useful Improvements in Tie-Plates for Use on Railways, of which the following is a specification.

My invention consists in providing a beveled tie-plate for placement on the tie of a railway and under the inner rail on curves in the road-bed, so that when in place on the tie and below the rail it will cant the inner rail under which it is placed into a vertical position, so that the tread of the inner rail will be directly above the center of the base-flange thereof, while the companion rail will incline slightly toward the center of the track; and the object of my invention is to provide a simple and reliable tie-plate therefor. I accomplish this object by means of the device described herein and shown in the accompanying drawings, in which—

Figure 1 is a perspective view of my improved tie-plate. Fig. 2 is a transverse section of a railroad-tie equipped with my improved tie-plate located under the inner or left-hand rail.

In the drawings, A is my improved tie-plate.

30 A' is that portion of the tie-plate forming the rest of the rail.

B represents an ordinary tie, upon which my tie-plate rests, and C represents the rails in place thereon. The tie-spikes D, which secure 35 the rail to the tie, pass through the apertures A" in the tie-plate. On the under part of the tie-plate I provide a number of longitudinal ribs A'", adapted to penetrate the tie and hold the tie-plate thereon from lateral movement

on the tie. In Fig. 2 the position of the rails 40 is shown. The dotted lines intersecting the center of the rails indicate the inclination of the rails on the ties. The rail C' on the left, being the inner rail, assumes a vertical position notwithstanding the tie B on which it is placed 45 lies at an angle to a horizontal plane. This position of the rail is secured by my improved tie-plate upon which this rail rests, the outer rail C" lying flat on the face of the tie, and therefore the tread thereof is inclined slightly 50 toward the center of the track.

Having described my invention, what I claim as new, and desire to secure by Letters Patent, is—

1. A tie-plate for railways comprising a 55 plate of iron or other suitable material having longitudinal ribs on the bottom thereof, a beveled rest for a rail on the top thereof and provided with apertures for the reception of tie-spikes. 60

2. A tie-plate for railways comprising a plate having a beveled rest for a rail on the top thereof, apertures therethrough for the reception of spikes, and provided with longitudinal ribs on the bottom thereof. 65

3. The herein-described tie-plate A having a beveled upper face A' forming a rest for a rail, the plate being provided with longitudinal ribs A"" on the under side thereof, substantially as herein described. 70

In witness that I claim the foregoing I have hereunto subscribed my name this 13th day of August, 1904.

ARTHUR A. MOTT.
